Inventor:

Richard B. Cavanagh,

By his Attorney,

F. W. Barnacle,

UNITED STATES PATENT OFFICE.

RICHARD B. CAVANAGH, OF WASHINGTON, DISTRICT OF COLUMBIA, ASSIGNOR, BY MESNE ASSIGNMENTS, TO THE KEMPSHALL MANUFACTURING COMPANY, A CORPORATION OF NEW JERSEY.

GOLF-BALL.

SPECIFICATION forming part of Letters Patent No. 710,752, dated October 7, 1902.

Application filed July 30, 1902. Serial No. 117,606. (No model.)

To all whom it may concern:

Be it known that I, RICHARD B. CAVANAGH, a citizen of the United States, residing in Washington, in the District of Columbia, have

5 invented certain new and useful Improvements in Golf-Balls, of which the following is a specification.

This invention relates to golf-balls; and its object is to produce at low cost a durable ball 10 which has good flying power.

In the accompanying drawings, Figure 1 illustrates, partly in section, a golf-ball made in accordance with my present invention; and Fig. 2 shows another form of center piece.

15 Upon a center piece A, preferably of soft rubber and preferably having a center A' of metal or other hard material, I apply a thick sphere B, consisting of paper or paper-pulp. The sphere B is highly compressed and may, 20 if desired, be formed in segments and then united under great pressure upon the center piece A. I then apply a gutta-percha shell C under heat and pressure in such a manner as to hold the filling B under high compression. At the operation of applying the 25 shell C the gutta-percha is softened by the heat, and the paper filling B is caused to join firmly to said shell, practically all over the interior surface thereof, thereby making the ball of good flying quality and great durability.

At Fig. 2 is illustrated a center piece D, which may be used instead of the soft rubber A and which consists of a mixture of

35 granules of cork E and granules of rubber F mixed with a suitable cement G of rubber or of a compound of glue and glycerin or of other suitable material.

Having described my invention, I claim—

1. A golf-ball comprising a soft centerpiece, 40 a hard center therewithin, a thick sphere thereon of compressed paper, and a shell of gutta-percha which adheres to the paper.

2. A golf-ball comprising a soft-rubber centerpiece, a hard center therewithin, a thick 45 solid sphere of paper thereon, and a shell of gutta - percha which adheres to the paper sphere.

3. A golf-ball comprising a sphere of paper, said sphere being formed of half-shells, a soft, 50 springy center piece, a hard center within said center piece, and a gutta-percha shell.

4. A golf - ball comprising a center piece formed at least partially of soft rubber, a hard center within said center piece, a thick sphere 55 thereon of compressed paper, and a shell of gutta-percha which holds said paper sphere under compression.

5. A golf-ball comprising a springy center piece having a metal center, a sphere thereon consisting of compressed paper, and a shell of gutta-percha which adheres to the paper sphere and holds the same under compression. 60

RICHARD B. CAVANAGH.
